UNITED STATES PATENT OFFICE.

WALLOCK V. ZARNEKEE, OF DETROIT, MICHIGAN.

RAIL-JOINT.

1,250,112.

Specification of Letters Patent. Patented Dec. 11, 1917.

Application filed October 8, 1917. Serial No. 195,399.

To all whom it may concern:

Be it known that I, WALLOCK V. ZARNEKEE, a citizen of the United States, residing at Detroit, in the county of Wayne and State 5 of Michigan, have invented certain new and useful Improvements in Rail-Joints, of which the following is a specification, reference being had to the accompanying drawings.

10 This invention relates to certain improvements in rail joints and has relation more particularly to a device of this general character wherein is included a tread bridge piece and it is an object of the invention to 15 provide a novel and improved rail joint wherein "pounding" is substantially entirely eliminated as the rolling stock passes thereover.

It is also an object of the invention to 20 provide a novel and improved rail joint wherein a tread bridge piece co-acts with the meeting ends of the rails and partially straddles the web portions thereof together with fish plates or splice bars co-acting with 25 the meeting ends of the rails for maintaining the tread bridge piece in applied position.

The invention consists in the details of construction and in the combination and arrangement of the several parts of my improved rail joint wherein certain important advantages are attained and the device rendered simpler, less expensive and otherwise more convenient and advantageous for use, 35 as will be hereinafter more fully set forth.

The novel features of my invention will hereinafter be definitely claimed.

In order that my invention may be the better understood I will now proceed to describe the same with reference to the accompanying drawings wherein:

Figure 1 is a view in top plan illustrating a rail joint constructed in accordance with an embodiment of my invention;

45 Fig. 2 is a view in side elevation of my improved joint with one of the fishplates or splice bars removed and the co-acting bolts shown in section;

Fig. 3 is a sectional view taken substantially on the line 3—3 of Fig. 1;

50 Fig. 4 is a view in perspective of one of the fishplates or splice bars as herein employed;

Fig. 5 is a view in perspective of the tread piece as herein embodied; and

Fig. 6 is a view in perspective of the meet-

ing ends of the rails as comprised in my improved joint.

As herein disclosed the rails R are of any ordinary or suitable construction and for a short distance back from each end the tread of each of the rails is cut away as indicated at 1 said cut portion extending slightly within the upper portion of the web 2 of the rail. The cut through a tread of each of the rails 65 is preferably diagonal as indicated at 3.

The tread bridge piece T comprises a tread 4 of the same configuration in cross section as the treads of the rails R and is of a length substantially equal to the combined 70 length of the cut away portions 1 at the meeting ends of the rails. As is illustrated particularly in Fig. 3 the tread bridge piece T is initially of a length slightly less than the combined length of the cut away portions 1 in order to compensate for expansion. The opposite ends 5 of the tread bridge piece 75 T are also cut diagonally to correspond with the cuts 3 in the treads of the rails R so that when the tread T is in applied or assembled 80 position a continuous tread is afforded notwithstanding the space allowed for expansion, as will be readily understood.

Depending from the tread bridge piece T are the transversely spaced flanges 6 extending the entire length of the tread bridge piece 10 and which are adapted to overlie the opposite faces of the webs 2 of the rails R. The flanges 6 are each of a width less than the width or height of the webs 2 of the 90 rails as is particularly illustrated in Figs. 2 and 3 of the accompanying drawings. Each of the flanges 6 adjacent its opposite ends is provided with the openings 7 adapted to register with the openings 8 produced 95 in the webs 2 of the rails below the cut away portions 1 thereof.

Co-acting with the meeting ends of the rails and arranged at each side thereof is a fishplate or splice bar B. The splice bar B 100 includes a web portion 9 provided along its upper marginal portions and at its opposite ends with the inwardly directed flanges 10. The inner ends of the flanges 10 are spaced apart, as at 11 a distance substantially equal to the length of the tread bridge piece T so that the adjacent flange 6 of the bridge piece T will afford no obstruction to the application of the fishplate or splice bar B into applied position. The upper edge of the web 105 9 and the flanges 10 preferably engage the under faces of the tread T of the meeting 110

ends of the rail while the lower marginal portion of the bar B is provided with an outstanding flange 12 resting directly upon the adjacent base flanges 14 of the rails R. The outer longitudinal margin of the flange 12 is downwardly directed as at 15 and is integrally connected with the plate 16 extending the entire length of the fishplate or splice bar B and underlying the rails R as is particularly illustrated in Fig. 3 of the accompanying drawings.

Each of the fishplates or splice bars B below the space 11 afforded between the flanges 10 is provided with the openings 17 adapted to register with the openings 7 and 8 hereinbefore referred to and insertible through each set of registering openings 7, 8 and 17 is the bolt 18 having co-acting therewith a clamping nut 19. As is particularly illustrated in Fig. 1 it is preferred that the bolts 18 be oppositely directed.

The fishplates or splice bars B when in applied position and engaged with the bridge tread piece T as hereinbefore disclosed through the medium of the bolts 18 and co-acting nuts 19 serve to effectively maintain the bridge tread piece T in applied position although it has been found of advantage to provide the outer end portions of each of the fishplates or splice bars B with the openings 20 adapted to register with the openings 21 disposed through the web portions 2 of the rails inwardly of the cut away portions 1. Directed through the registering openings 20 and 21 are the bolts 22 having co-acting therewith the clamping nuts 23. It is also preferred that the bolts 22 be reversely directed and also reversely directed relative to the adjacent bolts 18.

From the foregoing description, it is thought to be obvious that a rail joint constructed in accordance with my invention is

particularly well adapted for use by reason of the convenience and facility with which it may be assembled and operated and it 45 will also be obvious that my invention is susceptible of some change and modification without materially departing from the principles and spirit thereof and for this reason I do not wish to be understood as limiting 50 myself to the precise arrangement and formation of the several parts herein shown in carrying out my invention in practice except as hereinafter claimed.

I claim:

In a rail joint, the combination of meeting ends of rails having their tread portions cut away, a tread bridge piece fitting within the cut away portions of the treads, said bridge piece being provided with transversely spaced flanges overlying the opposite faces of the webs of the meeting ends of the rails, splice bars co-acting with the opposite sides of the webs of the rails and overlying the depending flanges of the tread piece, and fastening members disposed through the splice bars, the flanges of the tread bridge piece and the webs of the rails, said splice bars contacting with the base flanges of the rails and the under faces of the treads of the 70 rails, the upper marginal portions of the splice bars being provided at their opposite end portions with longitudinally spaced and inwardly directed flanges, the space between said flanges being substantially equal to the 75 length of the tread bridge piece, the flanges of the tread bridge piece being arranged within said spaces.

In testimony whereof I hereunto affix my signature in the presence of two witnesses. 80

WALLOCK V. ZARNEKEE.

Witnesses:

MOSES H. FAUBERT,
STEPHEN KROCHMAN.
